(57) **CLAIM**

The ornamental design for a flexi-shaped radio, as shown.

DESCRIPTION

FIG. 1 is a front perspective view showing my new design.

FIG. 2 is a rear perspective view thereof.

FIG. 3 is a front view thereof.

FIG. 4 is a rear view thereof.

FIG. 5 is a left end view thereof.

FIG. 6 is a right end view thereof.

FIG. 7 is a top view thereof.

FIG. 8 is a bottom view thereof.

FIG. 9 is a top view showing the extended antenna thereof.

FIG. 10 is a right view showing the extended antenna thereof.

FIG. 11 is a front view showing the extended antenna thereof.

FIG. 12 is a left view showing the extended antenna thereof; and,

FIG. 13 is a rear view showing the extended antenna thereof.
